UNITED STATES PATENT OFFICE.

WILLIAM J. PARK AND FRANK H. ROBINSON, OF CLEVELAND, OHIO.

REMOVABLE LABEL AND TRANSPARENT PANEL HOLDER FOR CAKE BOXES.

Application filed August 20, 1919. Serial No. 318,733.

To all whom it may concern:

Be it known that we, WILLIAM J. PARK and FRANK H. ROBINSON, citizens of the United States, residing at Cleveland, in the 5 county of Cuyahoga and State of Ohio, have invented certain new and useful Improvements in Removable Label and Transparent Panel Holders for Cake Boxes, of which the following is a specification.

10 This invention relates to cake or biscuit boxes or tins, such as are employed by various bakery companies to retain and display their goods in retail stores, and which boxes or tins are also employed in the shipment of 15 the cakes, biscuits or the like.

An object of the invention is to provide a removable front for boxes or tins of this nature which carries a label or suitable indicia indicating the name of the biscuit 20 company, the name or type of the cake contained therein or any other analogous indicia as desired, and which also removably carries the transparent panel, by means of which a portion of the contents of the box 25 or tin are disposed to view.

In cake boxes or tins of this type, now universally in use, the front of the boxes which carry the said indicia and transparent panel are formed with the remaining portions of the box so that when the said box 30 or tin is used for containing types of cake or biscuits other than that which was just previously contained therein, it is necessary to paste new labels thereon and after continued use of the box or tin, it is necessary 35 to first remove the old label before the new one can be properly placed thereon and it is an object of this invention to provide a removable holder for the labels and transparent panel which may be quickly and 40 easily connected to or disconnected from the tin or box; eliminating the necessity of pasting new labels upon the box front or removing the old labels, thereby materially decreasing the expense of such work and 45 consequently decreasing the quantity of labels necessary, in that the said holders are interchangeable with the box or tin structures.

More specifically, the invention comprehends the provision of a biscuit or cake box or tin, the front side of which is provided with a relatively large opening and which front side has its upper portion downturned and spaced to provide a recess for receiving 55 therein the upper end of the removable

holder, which holder is formed of sheet material, preferably tin and has indicated thereon a portion for retaining the label or receiving embossed indicia to impart any desired knowledge and which holder further 60 comprises means for removably containing a transparent panel permitting viewing of a portion of the contents of the box or tin.

Other objects of the invention will appear in the following detailed description taken 65 in connection with the accompanying drawings, forming a part of this specification and in which drawings:

Figure 1 is a perspective view of a cake box or tin having the improved removable 70 holder attached thereto.

Figure 2 is a vertical section through the front side of a cake box or tin showing the removable label and transparent panel holder in place, and 75

Figure 3 is a detail perspective showing the rear inner side of the removable one-piece label and transparent panel holder.

Referring more particularly to the drawings, A indicates an ordinary tin or box 80 used in containing various types of cakes, biscuits or the like and displaying them for sale, which has the usual type of hinged cover B. The front side C of the box A is provided with a relatively large rectangular opening indicated at 1 formed therein, the edge portions of the front side surrounding the said opening being instruck, if desired, as shown at 2 to increase the aesthetic value 85 of the box or tin.

The one-piece label or transparent holder, is indicated generically by the letter D and it fits within the box A against the inner surface of the front side C of the box as clearly shown in Figures 1 and 2 of the 90 drawings.

The upper edge portion of the front side C of the box A is extended inwardly and downturned, as clearly shown at 3 in Figure 2, forming a pocket 4 which receives therein 100 the upper edge of the removable holder D. This removable holder D is preferably formed of sheet metal, such as tin and its upper edge portion is extended inwardly and downturned as shown at 5 for engagement against the inner surface of the downturned portion 3 of the front side C while the said holder is engaged, inwardly of its edges by the instruck portion 2 of the front C, 105

The holder D is provided with a cut out portion 6, near its lower edge which is preferably rectangular in shape, being of equal width to the opening 1 in the front C of the box A, and the edges of the holder D surrounding the said opening are preferably slightly rolled inwardly as shown at 7 to add to the appearance of the holder and also to provide relatively spring or yieldable edge portions for contact with the removable transparent panel 8. The portion of the holder D along the upper edge of the opening 6 is bent or shaped to form a guide 9 substantially the shape of an inverted U which 15 guide 9 receives the upper edge of the transparent panel 8. The ends of the transparent panel 8 are engaged in guides 10 and 11 formed along each side edge of the panel D by the bending of the metal by which the 20 panel is formed. The lower edge of the holder D is free from the guiding flange analogous to the flanges 9, 10 and 11, and the material of which the holder is made is bent back upon itself at its lower edge and 25 an ear or tongue 12 is soldered or otherwise suitably attached thereto, or if preferred, it may be made from the material from which the holder is formed, as shown in Figure 2 of the drawings, without departing 30 from the spirit of this invention.

The portion of the holder D below the opening 6 is relatively flexible and may be flexed outwardly sufficient distance intermediate its edges to allow the transparent panel 8 to slip over the tongue 12 during the inserting of a transparent panel in the respective guiding and retaining flanges of the holder. However, after the lower edge 35 of the transparent panel has been moved above the tongue, the lower portion, indicated by the number 13, is reflexed to its normal position and the tongue 12 which is bent upon itself as clearly shown in Figure 2 engages beneath a lower edge of the transparent panel 8 preventing this panel from 40 sliding out of its guiding flanges when the panel D is removed from the box or tin A.

The portion of the holder D above the opening 6 therein is provided with an outstruck portion 14 which is preferably forced inwardly from the outer face of the holder D as clearly shown in the drawings, the flat surface of said outstruck portion being adapted to carry suitable indicia as indicated at 15 in Figure 1. This indicia 15 may be embossed upon the flat portions of the outstruck portion 14, or may be in the form of a label pasted thereon if desired.

In placing a one-piece label and transparent panel holder D in one of the boxes or tins A, the upper edge of said holder is inserted within the space 4 as shown in Figure 2 of the drawings, after which the lower edge of the panel D is moved inwardly into engagement with the inturned portion 2 of

the front C, the said inturned portion being slightly resilient the upper portion of the removable holder D will be engaged between the downturned portion 3 of the front C and the inturned portion 2 of the upper part of the opening 1, while the lower edge of the holder as well as the side edges will frictionally engage the sides or bottom of the tin or box A securely holding the holder D in place. To remove the holder D it is only necessary to push its lower end inwardly, then slip its upper end out of the recess or space 4.

Changes in details may be made without departing from the spirit of this invention, but:

We claim:

1. As a new article of manufacture, a removable one-piece label and transparent panel holder for cake boxes formed of sheet material, a transparent panel, guiding and retaining flanges formed upon said holder for engagement along the ends and the upper edge of said transparent panel, and a resilient tongue formed upon the rear surface of the holder at its lower edge for engagement with the lower edge of said transparent panel.

2. As a new article of manufacture, a removable one-piece label and transparent panel holder for cake boxes formed of sheet material, a transparent panel, guiding and retaining flanges formed upon said holder for engagement along the ends and the upper edge of said transparent panel, a tongue formed upon the rear surface of the holder at its lower edge for engagement with the lower edge of said transparent panel, said holder having an indicia carrying portion offset thereon above the opening therein.

3. In combination, a cake box having a front side provided with a relatively large opening, the upper portion of said front side extended inwardly and downwardly, a removable one-piece label and transparent panel holder, having its upper edge placed between the inner surface of the front side and said downwardly extended portions, said holder formed of sheet material and provided with an opening therein, guiding and retaining flanges formed along the ends and upper side of said opening, a transparent panel having its edge portion engaged in said flanges and adapted to register with a portion of the opening in the front of said box, a tongue carried by the lower edge of said holder and engaging a portion of the lower edge of said transparent panel.

4. A removable transparent panel and label holder for cake and cracker boxes comprising a rectangular metallic body plate, rearwardly and inwardly extending guide and strengthening flanges formed on the marginal side and top portions of the plate, the plate having a sight opening formed

therein adjacent to its lower end, a retaining flange carried by the inner surface of the plate directly above said sight opening, a transparent panel carried by the plate and 5 arranged to extend under the retaining flange, a resilient retaining tongue carried by the lower end of the plate for frictionally

engaging the transparent panel to hold the same against accidental displacement, and an indicia carrying portion struck in said 10 plate above said retaining flange.
